MEANS FOR LAYING COVERING ON SURFACES EXPOSED TO THE WEATHER

Andrew Ralph Craven, Philadelphia, Pa., assignor to Certain-Teed Products Corporation, New York, N. Y., a corporation of Maryland

Application February 25, 1931, Serial No. 518,058

6 Claims. (Cl. 33—187)

This invention relates to means for laying covering upon a surface, and more particularly to laying units of covering material exposed to the weather in spaced arrangement, and especially to laying units or strips of siding on exterior walls in overlapped spaced arrangement.

Covering units of various types, such as shingles or clapboards or asphalt shingles and strips simulating a group of shingles or other covering units, are usually laid in overlapped arrangement upon a roof or side wall or other exterior surface and also in a spaced arrangement. In general the spacing between successive strips in the overlapped arrangement is uniform to simulate the usual spacing of wood shingles, for example, laid individually and of substantially uniform length or to simulate constructions of clapboards or of brickwork or other masonry. Constructions having non-uniform arrangement may also be simulated in which the units are laid with non-uniform spacing. Arrangements of units without overlapping may also be used.

In the laying of such units and in assembling such constructions it is necessary or desirable that the proper spacing of the units or elements be obtained and, where a uniform exposure of the unit or element is desired, that the spacing or the uniform distance between the exposed edges of the successive units be maintained throughout the construction. With the usually practiced hand methods it is expensive and difficult, if not impossible, to obtain the desired spacing and therefore the desired effect of texture or design or other characteristic in the roof or other surface to be covered, as well as to insure weather tightness, without measurements for successive rows or positions of the units or elements. This difficulty is increased with units simulating brick-work, especially those which are provided with a groove to simulate the horizontal mortar joint and which are laid in an arrangement having the lower edge of an overlapping unit substantially coincide with the upper edge of the mortar joint simulated on the unit beneath. Similar problems arise in the laying of different types of units.

One object, therefore, of the present invention is to provide a means of locating the units being laid in proper relation to each other upon a surface.

Another object of the invention is to provide a means for holding the units being laid in proper position in relation to the surface for fastening thereto.

Another object of the invention is to provide a means of temporarily holding the strips of sur-

face covering material in position against a surface in spaced relation to strips or units previously laid.

A further object of the invention is to provide means for laying a plurality of units in a predetermined spaced relation upon a surface without measurement of the spacing between the successive units.

In accordance with my invention I therefore provide a means so supported or held in relation to the surface to be covered that it serves as a guide for laying or as a supporting means for the units being laid, so that said units when placed in position in relation to said guide will be properly located upon the surface and maintained in such relationship until they are fastened to the surface by suitable means. The guide or supporting means is preferably removably held in position for supporting or guiding the laying of the units while being laid and preferably is of such form that a plurality of units may be placed in position ready for fastening to the surface with one placement of the guiding or supporting means.

In a practical embodiment of my invention I prefer to use an elongated member having such cross section and of such material that it will be substantially stiff or rigid throughout its length and thereby provide a substantially constant guiding edge or supporting surface against which or upon which the units may be set or supported. Such an elongated member, for example, may take the form of a beam, such as an angle iron, placed against the surface and supported by hangers from brackets or hooks fastened to the uncovered portion of the surface.

The invention may find other embodiments and the support for the elongated member in relation to the surface may be provided by separate supporting means suitably placed in relation to the surface and to the member to properly hold the member in position against the surface as described. For example, instead of providing brackets fastened to the uncovered portion of the surface, I may provide independent supports upon which the hangers may be fastened. Such independent supports, for example, may consist of columns or posts suitably located and fixed temporarily in relation to the surface to be covered, so that when the elongated member or beam is supported thereby it will be properly positioned in relation to the surface.

The method of using my invention consists in locating the elongated member in such relation to the first unit or set of units to be laid upon the surface that when said unit or units are set

against the guiding edge or rest upon the elongated member they will be in position to be fastened to the surface. For example, a row of units in the form of strips simulating brickwork may rest 5 edgewise upon an elongated member provided with a straight edge and of considerable length. All or a number of the brickwork simulating units comprising a row of units or representing a course of brick in the wall may be laid while the elongated 10 member is in this initial position. By suitable spacing means, such as will be hereafter described, the elongated member may then be moved to the next succeeding position corresponding to the adjacent unit or row of units above upon the wall. 15 All or a number of the units in this row, i. e. the course of bricks, may be laid by placement against the guiding edge of the elongated member and then fastening to the wall. Similarly, upon moving the elongated member to the next successive 20 position a third row of units may be laid. Repetition of these steps for the successive rows or courses will provide the desired covering for the wall.

In order to provide for the proper spacing between the successive positions of the elongated member and thereby insure the desired or predetermined spacing of the units, for example, the spacing of the successive courses of brickwork, I may provide, in connection with the hangers supporting the elongated bar, spaced supporting means which I bring into successive cooperative positions in relation to the hooks or brackets herefore mentioned or their equivalent. I thus may predetermine the spacing between the successive 30 units, or, if desired, I may modify the predetermined spacing by adjustment of the spacing means in relation to the hangers or in relation to each other or by changing the relation of the hanger to the elongated member.

40 The particular means and combination of parts which I prefer for accomplishing these results, as well as the method of using the device in various ways, will be clear from a further description in connection with the drawing in which—

45 Fig. 1 shows my device as used for assembly of units upon a wall to simulate brickwork.

Fig. 2 is a cross section on line 2—2 of Fig. 1.

Fig. 3 shows a modified form of my device as used to assemble units, such as clapboards, 50 upon a wall.

Fig. 4 is a cross-section of Fig. 3 on line 4—4.

Fig. 5 is an enlarged view of the elongated member and a hanger attached thereto.

55 Fig. 6 is an enlarged view of the upper end 55 of the hanger showing the adjustable spacing means.

In Fig. 1 is shown an assembly of strips such as are usually made of roofing felt coated with asphalt, upon which coating is applied granular 60 surfacing material such as slate to represent the exposed faces of brick and to protect the coating and the felt base. In certain forms of such strips a horizontal groove is provided in the asphalt coating to simulate a horizontal joint of the 65 brickwork, and the vertical joint of brickwork is simulated by the cut-out formed in the exposed portion of the strip between the brick simulating tabs. In order to provide the simulation of the mortar in the joints, the overlapped portion of 70 the strip is coated with granular material of a suitable color and grain size and the groove simulating the horizontal joint of the brickwork may be similarly treated to give the appearance of a mortar joint.

75 An assembly of such units is shown in Fig. 1

as an example of the use of my invention. The strips 1 are provided with a groove 2 lengthwise thereof and slots or cut-outs 3 transverse to the edge of the strip and extending therefrom to the lower edge of the groove to represent the vertical joint of the brickwork. These slots separate tabs 4 of suitable length to represent the length of a brick, and the length of the slots corresponds to the depth of a brick, the horizontal groove being formed at a distance from the exposed edge of the strip to set off the depth of the tab equal to the depth of the brick. It will be seen that strips of this type are intended to be assembled in overlapped arrangement with the bottom edge of an overlapping strip substantially coincident with the upper edge of the groove. The overlapped area 5 of the strips may then be seen through the slots 3. When this overlapped area is surfaced with a suitable material of contrasting color to the brick, for example, sand or crushed light colored brick, brickwork having uncolored cement mortar joints is simulated. In such cases the horizontal groove formed in the asphalt coating may also be surfaced and represents the horizontal mortar joint of brickwork of the type described.

5 In using my device in connection with the laying-up of units in such an overlapped arrangement in which, as will be seen, a substantially uniform spacing between the lower edges of the successive strips or courses of units is desired, I may place my guiding device so that the elongated member 11 thereof is properly located along a line on the wall at which the bottom edge of a brick course is to be represented. The hangers 12 which may be fastened in suitable relation at different points along the length of the member 11 are suspended upon suitable brackets 13 as shown in Figs. 2 and 3 supported by the wall to be covered and above the units being laid. The hangers 12 may be so formed as by bending that the portion of their length adjacent to the bracket 13 bears against the surface of the wall, whereas the portion adjacent to the elongated supporting member 11 of my device is removed 45 from the wall to form a clear space above the upper surface or guiding edge of the elongated member 11 in which the unit or units being laid may be placed. As shown in Fig. 2, the hangers 12 may be formed of a flat bar bent so that the portion adjacent to the supporting bracket lies flat against the wall, whereas the portion adjacent to the guiding member 11, which in the embodiment illustrated in Figs. 1 and 2 is a beam of angle section, may lie flat against and be fastened to the vertical flange of said angle. It will be seen from Figs. 1 and 2 that the member 11 by 50 its weight bears against the wall and that the horizontal flange of the angle 11 forms a support for the strips 1 to hold them in position ready for nailing to the wall. It will also be seen that when said strips are resting edgewise upon the upper face of the horizontal leg of the angle they are correctly positioned relative to the groove of the strip next below, so that all the strips when placed in a row horizontally along the guiding member 11 will have their bottom edges substantially coincident with the upper edge of the horizontal groove or simulated mortar joint.

55 When the desired number of strips in such a horizontal row or course have been laid or suitably fastened to the wall, the guiding member or support 11 is raised to the next position for laying the next successive horizontal row of strips to form the next course of the brickwork. The 60

positioning of the horizontal guiding member relative to the course just laid may be accomplished by setting the top edge of the angle iron so as to coincide with the upper edge of the horizontal mortar joints of the course just laid and then fastening the hangers to brackets placed in new positions on the wall so as to hold the horizontal member in position. I may, however, so form the hangers and arrange for their cooperation with the brackets that I may, without the necessity of measurement or adjustment, raise the elongated guiding member to the next successive position without delay and so as to insure an accurate placement of the guiding member in its new position, whereby to reduce the cost of laying of strips or units of this type and at the same time produce the desired effect in the covering for the wall.

To this end, in one embodiment of this feature of my invention I provide on the hangers 12 a series of holes 15 which, for the type of construction illustrated in Fig. 1, are placed distances apart corresponding or equal to the vertical spacing of the brick courses. The hangers 12 are fastened to the elongated member 11 so that they maintain the proper angular relation to said member, usually at right angles thereto, and therefore when the successive holes 15 are brought into engagement with the hooks or brackets 13, which retain their position in the wall, the guiding member 11 is raised distances successively equal to successive spaces between the successive holes 15. In the embodiment disclosed in Fig. 1, as stated above, this spacing is equal to the distance between the courses of brick, that is to say, between the upper line of the horizontal mortar joint of one course and the upper horizontal line of the mortar joint in the next course above or below. It will be seen, therefore, that no measurements will be necessary in order to lay successive rows of units and that the upper face of the angle iron forming the guiding member 11 will be brought into substantial coincidence with said upper edge of the horizontal mortar joints by the simple act of hanging the hangers 12 upon the hooks 13. When, therefore, the units in the row being laid are set edgewise upon said upper face of the angle 11, the bottom edge of the unit or strip will be brought into substantial coincidence with said upper edge of the horizontal mortar joint. It will therefore be clear that the desired degree of overlap will be obtained without necessity for alignment or measurement and that in the particular embodiment being described attention need only be given to the desired horizontal relationship between the brick simulating spaces of the strips so as to produce the desired type of brickwork bond. The type illustrated, being merely an example, is that of the usual "stretcher" courses. The invention is nowise limited to the particular type of construction simulated, and it will be clear from a study of Figs. 1 and 2, as well as the further description in connection with Figs. 5 and 6, that the invention is applicable to any type of units or strips which are laid in successive arrangements.

With certain types of units, for example certain types of brickwork bonds or non-uniform courses of masonry, or with uneven exposures of shingle or shingle simulating units or of clapboards and the like, a predetermined lack of uniformity may be obtained by spacing the holes 15 along the hangers 12 at spaces corresponding or equal to the desired uneven spacing of the units upon the surface. For example, a brickwork con-

struction in which at intervals courses of bricks on end, or placed edgewise in the wall, or with the usual bearing face exposed, may be simulated with the use of suitable units or strips, and said strips may be properly spaced and properly related as to both the number of normal or stretcher courses and as to the spacing provided for these courses, as well as the spacing provided for the odd courses, by correspondingly spacing the holes 15 along the hangers 12. It will be clear that in using the guiding device of my invention the workman in reaching the oddly spaced hole will at once know that the proper number of strips simulating the normal courses of brickwork have been laid and that the course about to be laid will require the units of odd character to represent the odd course or courses of brick. Similarly, uneven spacing and exposure of shingles to produce odd effects or desired textures in a roof or wall surface may be laid rapidly and accurately by ordinary workmen. The methods just described will be applicable not only in connection with brickwork or shingle constructions but also will be applicable to other types of units, with the advantages of rapid laying, resulting in low cost, and accuracy of reproduction of the desired effect, as well as the accurate reproduction of the effect over the whole surface to be covered. A more exact use of material, thus avoiding wastage, will be obtained for the various uses to which my invention may be applied and with the various embodiments which are within the scope of the invention.

Figs. 3 and 4, for example, show a modified form of the guiding member and the supporting hangers. The guiding member instead of being formed of an angle iron may, in the embodiment shown in these figures, be formed of wood or other suitable material in which the ledges 20 and 21 are cut longitudinally of the guiding member 11 on which may be rested two successive units such as clapboards in position for fastening to the wall. It will be clear from Fig. 4 that the lower unit 22 may be placed so as to rest on the lower ledge 21 and may be fastened in place upon the wall in the usual manner. Without movement of the guiding device 11 or its hangers 12 relative to the brackets 13, the next successive unit 23 may be placed so as to rest upon the ledge 20 and then fastened in place. The elongated member 11, upon which the units or a row of units have been rested and subsequently fastened as just described, may then be moved upward a distance corresponding to the spacing of two units. Such a movement will bring the lower ledge 21 in line for the next successive unit adjacent the last laid unit 23, and the ledge 20 will then be in position to receive the second successive unit to the last laid unit 23. The operation of laying the units may be repeated for the new position of the guiding member or bar 11. It will now be clear that the spacing of the holes 15 instead of corresponding with the spacing of successive courses or rows of units upon the surface will be spaced to correspond with the spacing of their other row.

If the spacing of the holes 15 along the hangers 12 in Fig. 3 is uniform and equal to twice the spacing of the individual units upon the wall, a uniform spacing will be obtained. However, by varying the spacing of the holes along the hangers 12 modifications of the uniform spacing may be obtained in a similar manner to that described in connection with Figs. 1 and 2, the spacing of two units of the pairs of units, however, being

determined by the spacing between the ledges 20 and 21. Variations in the spacing between said ledges may be provided by substituting bars having different spacing of the ledges 20 and 21. Such modifications are within the scope of the present invention.

A further modification of the spacing or of the adjustment of the guiding edge or face of the elongated member 11 may be made by adjustment 10 of the angular relationship between the hangers 12 and said guiding member 11. For example, as shown in Fig. 1 and in greater detail in Fig. 5, I may so attach the hanger 12 to the angle 11 that said hanger pivots upon a pin 16 15 and is clamped by a wing nut 17 operating upon a stud 18 which passes through a curved slot 19 in the angle 11 so that the end of the hanger 12 may be clamped in various positions and therefore at various angles to the length of the guiding member or angle 11. At the right hand end 20 of Fig. 5 is shown the pin 16 upon which the right hand hanger 12 pivots with said hanger removed therefrom, and adjacent to said pin is shown the corresponding slot 19 from which also 25 the respective wing nut 17 and stud 18 have been removed. Other devices may be used within the scope of the invention to accomplish this purpose.

As an example of the adjustment referred to, the left hand hanger 12 may be placed at an 30 angle other than a right angle to the guiding member 11, while the right hand hanger 12 may be maintained at a right angle to said guiding member. With corresponding positions for the 35 brackets or hooks 13 upon the wall, the left hand end of the member 11 may be raised relative to the right hand end, thereby adjusting the level or alignment of said member 11 relative to the wall. It is also possible by suitably forming the 40 slots 19 to so position the hangers 12, for example at the same angle with the elongated member 11 and running in the same direction relative to the length of said member 11, that when the device is used in connection with brackets fastened upon a wall or surface in the manner described in connection with Figs. 1 and 2 45 the arrangement of successive courses will be that of units running parallel to each other but at an incline to the horizontal upon the surface or at other than a right angle to the direction 50 of the successive positions of the hangers. Variations of positioning of the guiding member 11 may also be utilized to vary along the length of the courses, for example in a horizontal direction, the spacing between successive courses. 55 Combinations of the variations produced by spacings of the holes along the hangers 12 with variations in the elevation of the bar or guiding member 11 may be made to produce particular arrangements of the units and special effects upon the surface. Such angular placements may also 60 be used to avoid interference with projecting portions of the wall surface to be covered, such as window frames, or to find lodgment for the brackets or hooks 13.

A further feature of the embodiment illustrated in Figs. 1, 2 and 4 provides for the forming of 65 the slot 19 in the form of an arc of a circle of such degree that the hangers 12 may be folded by pivoting about the pin 16 so as to lie along, or substantially along, the guiding member 11, so that without removal of the hangers 12 from engagement with said member 11 the whole device may be conveniently handled and transported. However, if desired the use of the wing

nut 17 and the stud 18 permits removal of the hangers from engagement with the bar 11, so that hangers of different form to suit particular conditions of the wall surface or to provide different spacings of the holes for engagement with the brackets 13 may be attached. The clamping action of the wing nut makes the whole device a rigid unit which therefore hangs in proper position and without swinging laterally. 5

Modifications both of the method of attachment to the guiding member 11, as well as to the wall, and of the hangers 12 themselves may be made within the scope of the invention to provide for different conditions. For example, while in the embodiment shown in the drawing I have used the simple device of nails driven into the woodwork of a wall to be covered by brickwork simulating units or by clapboards, upon which nails the hangers may be hung by simply slipping the proper holes over said nails, I may provide a bracket of such form that the point of its engagement with the hole of the hanger 12 is somewhat removed from the wall. In such case the bend formed in the hanger 12 may be reduced or eliminated. Other modifications may be 25 made in the form of the hanger 12 by suitable design of the brackets and the portion of the hangers engaging with said brackets. The arrangement of parts may be such that the weight of the device causes the elongated member 11 to swing 30 against the wall and hold the unit in place by pressing it against the wall.

In Fig. 6 is illustrated a particular form of the upper end of the hangers 12 which provides for adjustment of the spacing of the means on said 35 hangers for engagement with said brackets. In the particular embodiment shown in Fig. 6, I provide a slot 30 lengthwise of the hanger 12 in which are slidably arranged bushings 31 which have a hole 15 therein for engagement with the 40 bracket or hook 13 as heretofore described. The bushings 31 may be clamped by suitable means such as set screw 35, in order to properly position said bushings relative to the hanger 12. The set screw 35 bears upon the surface of the hanger 45 12 and draws the rear flange 36 of the bushing 31 against the rear face of said hanger 12 to clamp the bushing in the desired position. For convenience I provide a marker 32 for each bushing, which is suitably related to a scale marked upon 50 the hanger 12 along the slot 30. There is thus provided a means for adjustably positioning successive holes 15 while holding such holes in the proper relationship with each other to produce the desired spacing. It will be clear that variations in the spacing may thus be obtained of finer degree than that provided by the spaced holes along the hangers 12 as described in connection 55 with Figs. 1 and 2. There will thus be avoided in some cases the necessity of changing the 60 hangers 12 in order to obtain different spacings for different surfaces or types of work. It will be clear that when the bushings 31 are set in a pre-determined relation along the slots the guiding device of my invention may be used in a similar 65 manner to that described in connection with Figs. 1 and 2.

While I have described my invention particularly in connection with the laying of units in the form of strips of covering material such as 70 asphalt coated roofing strips surfaced with slate to simulate brickwork or in connection with clapboard simulating units, I may utilize the device of my invention to lay spaced units of other types such as wood clapboards or wood shingles upon 75

a roof or a side wall or other surface with the advantages of saving in the cost of laying, convenience in handling the units and accuracy of producing the desired result as mentioned above.

5 The guiding edge of the member 11 of my device will serve to properly position such units laid in overlapped arrangement. With similar advantages I may also use my device to guide the laying of units in spaced arrangement without over-lapping by using the guiding edge as a means of alignment. For example, by suitably supporting said guiding member 11 on posts as heretofore described, I may use the edge thereof as a line for the laying of courses of brick or masonry in place 10 of the usual mason's line. The invention may be applied to other uses and may find other embodiments than those illustrated and described herein which are, however, within the scope thereof.

20 Having described my invention, I claim:

1. A device for guiding the laying of a covering for a wall surface composed of units in a vertically spaced arrangement on the wall which comprises a plurality of weight sustaining means 25 each fixed in relation to the wall, hangers having a part of their extent depending each from one of said weight sustaining means, and a bar normally rigidly attached to said hangers at a point on each hanger spaced in the direction transversely of the bar a predetermined distance from the point thereon at which said hanger depends from its weight sustaining means, said weight sustaining means respectively being positioned at predetermined distances in the vertical direction 30 from the positions upon the wall of said units to be laid, said device being so supported by said weight sustaining means that upon said bar may be rested the lower edge of a unit in position to be laid upon said wall surface, each of said hangers at said point thereon at which the hanger depends from its weight sustaining means and at a plurality of points spaced therefrom in the direction transversely of the length of said bar being formed for selective removable engagement 35 with said weight sustaining means, the spacing on each hanger of said points at which said hanger is formed for selective removable engagement with its weight sustaining means being proportionate to the desired vertical spacing 40 of the units upon the wall.

2. A device for use in laying covering units in a plurality of spaced positions upon a supporting structure which comprises a guide in relation to which to position a unit, means fixed in relation 55 to said structure and determining a single point thereon spaced from said positions of the units in the general direction of the spacing of the units and in a predetermined relation thereto, and means normally rigidly connected to said guide 60 and providing at a plurality of points thereon spaced apart in the general direction of the spacing of the units means for selective removable engagement with said fixed means, said fixed means being formed and arranged for fixedly 65 holding in relation to said structure said guide and said means rigidly connected thereto when said means for removable engagement is engaged therewith, the spacing of said means for removable engagement upon said means rigidly connected to said guide being proportionate to the

desired spacing of the units upon the surface, whereby, upon engagement with said fixed means of the means for removable engagement at the different points on said rigidly connected means, different positions of the guide are determined for laying said units in the different spaced positions.

3. A device for use in laying covering units in spaced positions upon a surface to be covered which comprises a guide for positioning a unit 10 upon the surface, a member normally rigidly connected to said guide and having an extent generally in the direction of the spacing of the units from said guide, said member at a plurality of points thereon spaced apart in said general 15 direction being formed for selective removable engagement with a holding means, said holding means determining a single point fixed in relation to said surface at which said member may engage said holding means, said holding means 20 being formed and arranged so that it may be removably engaged by said member and fixedly to hold with respect to said surface said member and said guide rigidly connected thereto when said member is in said engagement with said holding 25 means, the spacing on said member of the points at which it is formed for said removable engagement being proportionate to the desired spacing of the units upon said surface.

4. A device according to claim 1 in which said 30 bar is formed with a flange portion extending substantially normal to the wall so that the edge thereof may rest thereagainst.

5. A device according to claim 3 in which said 35 member includes means adjustable thereon in the direction of the spacing of the units and formed for said selective removable engagement with said holding means, whereby the spacing on said member of said points of removable engagement with said holding means may be varied.

6. A device for use in laying a surface covering composed of units laid in courses upon the surface which comprises an elongated guide member arranged to be positioned lengthwise of the courses against which to abut the units to be laid 45 in a course, a plurality of means each fixed with respect to said surface and each determining a point thereon spaced from said course in a direction transversely of the course at a predetermined distance therefrom, and a plurality of positioning members each normally rigidly attached to said elongated member and extending transversely thereof to engage one of said fixed means at a point on said positioning member removed from the point of rigid attachment to said elongated member, said fixed means being constructed to hold the device fixed in relation to said surface when so engaged, said positioning members each providing at said point of engagement and at predetermined intervals therealong from said point of engagement in said direction transverse to said elongated member means for selective removable engagement with said fixed means, said intervals being proportionate to the desired intervals between the courses so that the elongated 60 member, for different points of engagement of said positioning members with their respective fixed means, may be positioned for fastening to the surface the units in the different courses.
